UNITED STATES PATENT OFFICE.

THOMAS BREEN, OF KNOWLTON, PENNSYLVANIA.

RAILWAY-SIGNAL.

SPECIFICATION forming part of Letters Patent No. 272,851, dated February 27, 1883.

Application filed April 17, 1882. (No model.)

To all whom it may concern:

Be it known that I, THOMAS BREEN, a citizen of the United States, residing at Knowlton, in the county of Delaware and State of Pennsylvania, have invented certain new and useful Improvements in Railway-Signals, of which the following is a specification, reference being had therein to the accompanying drawings, and in which—

10 Figure 1 is a plan view of my improved railway-signal as applied for use. Fig. 2 is a side view of the same, showing it in its two positions. Fig. 3 is a sectional elevation, and Fig. 4 is a front elevation. Figs. 5, 6, and 7 are detailed views thereof.

15 This invention relates to improvements in railway-signals, having for its object to effect the operation of the signals by the action of the wheels of the locomotive or cars; and it 20 consists in the mechanism through or by which the action of the car or locomotive wheels is transmitted to the signal proper, and details of construction, substantially as hereinafter more fully set forth and claimed.

25 To put into practice my invention I employ a case, A, preferably of the form shown, with one end made or provided with an upright rectangular tube or supplemental case, A', its upper end being left open.

30 B is the signal proper, which may be a flat bar or board, arranged in the upright tube or case A'. On, or rather in, the front side of the case or tube A' is a vertical slot, a. Through this slot projects a projection secured to the signal B, and having depending from its outer end a shade, b, to aid the dropping of the signal.

35 Hung upon a hook or bracket, (and to cover the lamp when it is not desired to display the signal,) c, of the upright tube A', to have conveniently at hand, is a colored-glass lamp, c', to be secured or supported upon the signal-frame at night.

40 C is a lever or rod pivoted in the upper part of one end of the case A, and having an outer curved or segmental arm, C', as clearly seen in Fig. 2. This arm is attached or formed upon a right-angled portion, C², bearing upon a support, d, arranged with relation to the case A, 45 to which it is secured. Further, this segmental or curved arm of the lever C is arranged, as clearly defined in Fig. 1, alongside of one rail

of the track on its outside. The signal apparatus or mechanism is therefore disposed a short distance from the track and parallel with it. This lever is curved downward from the right-angled arm or axis C² to and extends along the bottom of the case A forward a suitable distance, and curved into an eye or shoulder, e, at its free end. This shoulder or 50 end of the rod or lever C is arranged under the lower end of the signal or board B to enable it to act thereon. Further, said end is connected to a chain, D, or its equivalent, which is carried around a grooved friction roll or 55 pulley, D', and thence passed through a tube, f, to and connected to a distant rod, similar to the rod E, arranged in the case A, whose forward end is connected to a pawl or lever, F. The pawl and pulley have a common axis, and 60 are so arranged that the right-angled upper end or tooth of the pawl will, when the board or signal and that end of the lever C supporting it are elevated, effect the holding of the signal or board in its elevated position. A 65 spring, g, preferably secured to a disk or plate, h, covering an opening in the side of the case A, and to the pawl or lever F, springs the latter under the elevated signal.

70 It will be observed from the foregoing that as the wheel of the approaching locomotive or engine strikes and throws down the curved arm C' of the lever C the forward end of said lever will be instantly thrown up, elevating the signal B, giving warning to any train behind. 75 At the same instant the ascending end of the lever or rod C will draw upon the chain D, passed around the pulley D', causing it to revolve and pull a lever or pawl, similar to the pawl F, from under the signal, placed a mile 80 in the rear, and thus cause it to fall, warning any train behind. Thus it will be observed that should a train of cars pass signal A² and then break down between signal A² and A³, a mile apart, an approaching train from behind, 85 on reaching signal A², would be warned not to proceed, and hence the danger of a second train running into the broken-down train between the two stations would be avoided; also, simultaneously with the elevation of the 90 forward end of the lever or rod C and the signal-board B, the pawl F, whose tooth is held in forcible contact with the said board by the action of its spring, will be sprung under the 95

said end of the rod or lever C, and thus effect the holding of the same until tripped by a passing train, which sets it to "danger" as it leaves the other end of the block. The small 5 circular door or disk h, above referred to, to which the spring g of the pawl F is connected, permits the ready insertion in place and removal of the spring when necessary, as for renewal or other purpose. The disk or door 10 h is removably secured in place by a bolt, i, passed through the case A and screwed at its screw-threaded end into a female screw in an aperture, i', in the disk or door.

I claim and desire to secure by Letters Patent—

1. In a railway-signal, the combination of the lever having a curved arm, a right-angled cross-arm, and lateral extended arm, with eye e formed in the end of the same, with the 20 sliding signal-board whose lower end is arranged to rest on one end of said lever, as and for the purpose set forth.

2. In a railway-signal, the combination of the lever, constructed to operate as described, with the sliding signal-board and the spring-pawl, arranged to support the forward end of 25 said lever and the signal-board in an elevated position, substantially as and for the purpose set forth.

3. In a railway-signal, the combination of 30 the lever, constructed to operate as described, the sliding signal-board, the spring-pawl, and chain, or its equivalent, connected to the rod of the said lever, thence passed over a friction pulley or roll, and extended and connected 35 to a rod connected to a distant pawl supporting a sliding signal-board, substantially as and for the purpose specified.

In testimony whereof I affix my signature in presence of two witnesses.

THOMAS BREEN.
